UNITED STATES PATENT OFFICE

1,944,421

RAILWAY CAR

Garth G. Gilpin, Riverside, Ill., assignor to Union Metal Products Company, Chicago, Ill., a corporation of Delaware

Application October 28, 1929. Serial No. 402,936

3 Claims. (Cl. 105—249)

The invention relates to railway dump cars having doors at the lower ends of the hopper so that the load may be discharged by simply opening the doors.

5 An object of the invention is to provide such a railway dump car with an unobstructed hopper and hopper door opening extending between the side walls of the car and to make such an arrangement possible by eliminating the usual center sill construction and providing strong side walls to carry the weight of the car and its load to the body bolsters and to take care of the buffing shocks of coupling.

Another object is to provide a single casting comprising a body bolster and supports for the hopper floor positioned above the bolster and other supports for the hopper floor positioned laterally of the bolster.

Another object is to provide an integral casting comprising body bolster, draft sills, hopper floor supports, and diagonal braces extending between the ends of the draft sills and the bolster.

In the drawings:

Fig. 1 is a plan view of a typical car according to my invention wherein the floor plates are partially removed.

Fig. 2 is a section on line 2—2 of Fig. 1.

Fig. 3 is a section on line 3—3 of Fig. 1.

Fig. 4 shows on the left side a section on line 4—4 of Fig. 2 and on the right side an end elevation of the car.

Fig. 5 is a perspective view showing my construction.

The car illustrated comprises spaced apart body bolsters 2 performing the usual functions of such elements which are primarily to transfer the weight of the car and its load to the truck upon which it is supported in such a manner as to permit the truck to swivel under it when the car is rounding curves. I prefer to form the center or swivel plate 3, as well as the side bearings 4, as an integral part of the body bolster.

The side walls each comprise a load retaining plate 6, a top chord 7, and a lower chord (side sill structure) which members combine to form a side girder to transfer the load to the body bolsters. In my construction I eliminate the usual center sills and provide extra strong side sill constructions to perform their functions.

50 The side sill structures each comprise two beams secured together to form a box girder, the outer of said beams 9 being attached to the outer end of the body bolsters 2 and extending therebeyond, whereas the inner of said beams 10 is attached to the body bolsters adjacent their

outer ends. The body bolster is provided with a flange 11 and gusset 12 for such attachment. The draft sills 15, which in my construction, are integral with the body bolster, extend from the bolster to the end of the car and are secured to the end sill 16, which end sill is also secured to the extremities 17 of the outer beam 9 of the side sill construction. Diagonal braces 20 extend from the ends of the draft sills 15 to the ends of the body bolsters 2 and are also preferably cast integral with these elements.

I also cast the hopper floor support or cross bearers 21 integral with the body bolster member which extends upwardly from the top of the bolster and is provided with an upper web 22 parallel to the hopper floor 23 and secured thereto. This support also reinforces the bolster to carry vertical loads.

I also preferably extend the draft sills back (25) of the body bolster to the hopper floor 23 where the casting is provided with a web 26 parallel to the hopper floor and secured thereto. In this arrangement, therefore, the integral bolster member supports the hopper floor at two places. By terminating this casting at the hopper floor the hopper is permitted to extend the full width of the car between the side walls or at least between the side sill constructions.

The cross bearers 30 extend between the opposite side walls of the car and are secured thereto, as well as to the side sill constructions, by webs 31 and rivets 32. These cross bearers are provided with diagonal braces 33 so that they prevent the side walls from buckling or deflecting under load. They are preferably also provided with an extension 36 to which the top chord 7 is secured to hold it in alignment. The lower portion of this cross bearer is provided with downwardly inclined walls 37 so as to assist in bracing the car in a horizontal plane. These sloping walls are secured to the side sill constructions.

The doors 40 extend the full width of the hopper, that is, the distance between the side sill constructions, and are preferably hinged to the 100 sloping walls 37 of the cross bearer. Any convenient means may be used to operate and lock these doors.

The end wall 42 is supported by the end post 43 and corner post 44 and is provided with a top reinforcement 45.

The accompanying drawings illustrate the preferred form of the invention, though it is to be understood that the invention is not limited to the exact details of construction shown and

described, as it is obvious that various modifications thereof, within the scope of the claims, will occur to persons skilled in the art.

I claim:

- 5 1. In a railway car, the combination of spaced apart side sheets, spaced apart side sills, and a pair of substantially duplicate castings secured together adjacent the center of the car and secured to said side sills to form a cross bearer of the car, each of said castings formed with an integral diagonal brace extending from substantially the center of the car to the upper part of the side sheet to which it is secured.
- 10 2. In a railway car, the combination of spaced apart side sills, a pair of substantially duplicate castings secured together adjacent the center of the car and secured to said side sills to form a

cross bearer of the car, the lower margins of said castings formed into outwardly flared portions, and sloping floor sheets secured to said flared portions.

- 15 3. In a railway car, the combination of spaced apart side sills, a pair of substantially duplicate castings secured together adjacent the center of the car and secured to said side sills to form a cross bearer of the car, each of said castings formed with an integral diagonal brace extending from substantially the center of the car to the upper part of the side sheet to which it is secured, the lower margins of said castings formed into outwardly flared portions, and sloping floor sheets secured to said flared portions.

GARTH G. GILPIN.
